ATTORNEY'S

UNITED STATES PATENT OFFICE

DEZSÖ HORNYÁK, OF CLEVELAND, OHIO

FOUNTAIN PAINTBRUSH

Application filed February 20, 1929. Serial No. 341,537.

This invention relates to certain new and useful improvements in fountain paint brushes and has for its primary object to provide a paint brush comprising a hollow body portion into one end of which a handle is attached, while the other end supports a bristle carrying backing and adapted to contain a quantity of paint with means for automatically feeding the paint onto the brush 10 bristles.

A further object of the invention is to provide a fountain paint brush of the above type wherein the hollow body portion of the brush contains a tensioned plunger spring pressed 15 in one direction to permit the flow of paint therearound and to that part of the body portion forwardly of the plunger with manually operated means for the plunger operating against spring tension thereon to eject the 20 paint onto the brush bristles.

With the above and other objects in view, that will become apparent as the nature of the invention is better understood, the same 25 consists in the novel form, combination and arrangement of parts hereinafter more fully described, shown in the accompanying drawings and claimed.

In the drawings:—

Figure 1 is a side elevational view of a 30 fountain paint brush constructed in accordance with the present invention, the interior paint feeding mechanism illustrated by dotted lines;

Figure 2 is an edge elevational view of the 35 brush showing the body portion to be of increased diameter forming a chamber for the reception of a quantity of paint;

Figure 3 is a vertical longitudinal sectional view of the paint brush showing the tensioned 40 plunger and manually operating devices therefor;

Figure 4 is a cross-sectional view taken on line 4—4 of Figure 3;

Figure 5 is a cross-sectional view taken on 45 line 5—5 of Figure 3, showing the brush backing having bristle receiving openings and adjacent openings for the passage of paint; and

Figure 6 is a perspective view of the tensioned plunger for feeding the paint.

The fountain paint brush comprises a body

portion 1 oval in cross-section as shown in Figures 4 and 5 to provide an interior chamber 2 for paint or other liquid P, the body portion 1 being of any preferred size for holding different quantities of paint. The outer end of the wall of the body portion 1 is angularly recessed at its inner side as at 3 defining a shoulder 4. The brush backing 5 is of similar configuration in plan view to the cross sectional area of the body portion 1 and is 55 grooved at one end thereof as at 6 to seat in the recess 3 and engage the shoulder 4 as shown in Figure 3. A plurality of openings 7 are provided in the outer face of the brush backing 5 and are suitably distributed thereover in an arrangement, such as indicated in Figure 5 for the reception of brush bristles 8, the brush backing 5 being also provided with a plurality of openings 9 extending 60 completely therethrough shown in Figure 5 to permit the flow of paint from the chamber 2 to the brush backing 5 and onto the bristles 8 in a manner to be presently described. A 65 tapering guide flange 10 incloses the outer end of the body portion 1 and overlaps the adjacent ends of the brush bristles 8, the fastening screws 11 being employed for securing the guide flange 10 in position and also anchoring the brush back 5 in the body portion 1.

A handle is detachably mounted upon the inner end of the body portion 1 and to accommodate said mounting, the body portion 1 at its inner end is externally recessed upon the outer side thereof as at 12 to receive the edge flange 13 of the handle body 14 carrying a gripping handle 15. Fastening screws 16 or the like anchor the handle body flange 13 to the body portion 1. A threaded opening 17 in the handle body 14 permits charging 80 of the body portion 1 with paint P, and said opening is closed by the screw plug 18.

A rod 19 extends through the body portion and handle of the brush, the outer end thereof being threaded centrally through the brush backing 5 as at 20 with the nuts 21 threaded thereon engaging the outer face of the brush backing. The inner end of the rod 19 is threaded as at 22 and is seated in the threaded socket 23 provided in the handle cap 24.

The plunger 25 shown in detail in Figure 6 of a configuration in plan view similar to the cross sectional area of the body portion 1 and of slightly less diameter than the interior diameter of the chamber 2 as shown in Figure 3 is disposed in said chamber 2 and has a depending edge flange 26 slightly spaced from the walls of the chamber 2. The plunger 25 is provided with a central opening surrounded by an upstanding tube 27 having an inwardly directed annular flange 28 on its upper end. The tube 27 surrounds the rod 19 and is spaced therefrom, the plunger 25 being guided in its sliding movement on the rod 19. 10 A coil spring 29 encloses the rod 19 between the brush backing 5 and flange 28 upon the tube 27, normally influencing the plunger 25 in an upward direction toward the paint brush handle. A relatively long tube 30 encloses the rod 19 between the upper end of the tube 27 and handle cap 24, the tube 30 extending upwardly through an opening in the handle body 14 and handle grip 15 and engaged at its upper end by the handle cap. 15 Paint or other liquid is introduced into the chamber 2 of the fountain brush through the opening 17 that is closed by the screw plug 18. When the handle cap 24 is partly unthreaded from the inner threaded end 22 of the rod 19, 20 the spring 29 raises the plunger 25 and tube 30, said movement being limited by unscrewing movement of the handle cap 24. During upward movement of the plunger 25 into the body of paint P, the air in the space between the upper level of the paint and the body 14 will be partly compressed and force the paint around the flanged edge 26 of the plunger to occupy the area between the plunger and brush backing 5 as indicated in 25 Figure 3. The handle cap 24 is then screwed onto the rod 19 and during such movement returns the tube 30 to the position shown in Figure 3, and forces the plunger 25 in a direction toward the brush backing 5 to cause the paint forwardly of the plunger to be forced through the openings 9 in the brush backing 5 and onto the bristles. The amount of paint projection may be controlled by the unscrewing of the handle cap 24 and the length of 30 movement of the tube 30 away from the brush backing.

While there is herein shown and described the preferred embodiment of the present invention, it is nevertheless to be understood that minor changes may be made therein without departing from the spirit and scope of the invention as claimed.

I claim:

1. In a fountain paint brush, a chambered body, a perforated brush backing at the outer end of the body, a handle at the inner end of the body, a plunger in the chambered body, means tensioning said plunger toward the handle end of the brush, means extending through the handle and operable from the in-

ner end thereof to move the plunger toward the brush backing to discharge paint there-through, said means including a rod on which the plunger is slideable, a handle cap threaded on the inner end of the rod, and an elongated tube inclosing the rod between the plunger and handle cap. 70

2. In a fountain paint brush, a chambered body, a perforated brush backing at the outer end of the body, a handle at the inner end of the body, a plunger in the chambered body, means tensioning said plunger toward the handle end of the brush, means extending through the handle and operable from the inner end thereof to move the plunger toward the brush backing to discharge paint there-through, the plunger being of less diameter than the chambered body, said means including a rod on which the plunger is slideable, a handle cap threaded on the inner end of the rod, and an elongated tube inclosing the rod between the plunger and handle cap. 75 80

3. In a fountain paint brush, a chambered body, a perforated brush backing at the outer end of the body, a handle at the inner end of the body, a plunger in the chambered body, means tensioning said plunger toward the handle end of the brush, means extending through the handle and operable from the inner end thereof to move the plunger toward the brush backing to discharge paint there-through, said means including a rod on which the plunger is slideable, a handle cap threaded on the inner end of the rod, an elongated tube inclosing the rod between the plunger and handle cap, the brush backing having paint openings therethrough spaced from the brush bristles, and the handle having a paint filling opening for the chambered body. 90 95 100

4. In a fountain paint brush, a chambered body, a perforated brush backing at the outer end of the body, a handle at the inner end of the body, a plunger in the chambered body, means tensioning said plunger toward the handle end of the brush, means extending through the handle and operable from the inner end thereof to move the plunger toward the brush backing to discharge paint there-through, the plunger being of less diameter than the chambered body, said means including a rod on which the plunger is slideable, a handle cap threaded on the inner end of the rod, an elongated tube inclosing the rod between the plunger and handle cap, the brush backing having paint openings therethrough spaced from the brush bristles, and the handle having a paint filling opening for the chambered body. 105 110 115 120 125

In testimony whereof I affix my signature.
